US0D1070589S

(12) **United States Design Patent** (10) **Patent No.:** **US D1,070,589 S**
(45) **Date of Patent:** **** Apr. 15, 2025**

(54) **INSERT FOR PACKAGING CARTON**

(71) Applicant: **The Procter & Gamble Company**,
Cincinnati, OH (US)

(72) Inventors: **Clara Sophie Lea Ng Pak Leung**,
Ixelles (BE); **Raf Gustaaf Alfons Degeyter**, Herk-De-Stad (BE); **Paulus Antonius Augustinus Hoeft**, Astene (BE)

(73) Assignee: **The Procter & Gamble Company**,
Cincinnati, OH (US)

(**) Term: **15 Years**

(21) Appl. No.: **29/953,086**

(22) Filed: **Jul. 19, 2024**

Related U.S. Application Data

(63) Continuation of application No. 29/815,656, filed on Nov. 16, 2021, now Pat. No. Des. 1,044,497.

(57) **CLAIM**

The ornamental design for an insert for packaging carton as shown and described.

DESCRIPTION

FIG. 1 is a perspective view of an insert for packaging carton, showing our new design;

FIG. 2 is a front view thereof;

FIG. 3 is a back view thereof;

FIG. 4 is a right view thereof;

FIG. 5 is a left view thereof;

FIG. 6 is a top view thereof;

FIG. 7 is a bottom view thereof;

FIG. 8 is a perspective view of the insert for packaging carton, shown in a position of use with an exemplary packaging carton;

FIG. 9 is a front view thereof;

FIG. 10 is a back view thereof;

FIG. 11 is a right view thereof;

FIG. 12 is a left view thereof;

FIG. 13 is a top view thereof; and,

FIG. 14 is a bottom view thereof.

The broken lines are shown for the purpose of illustrating parts of the article as well as environmental subject matter of an exemplary packaging carton. None of the broken lines form part of the claimed design.

1 Claim, 5 Drawing Sheets
